UNITED STATES PATENT OFFICE.

JAMES F. MACWILLIAM, OF WORCESTER, MASSACHUSETTS.

COP-WINDER.

1,105,151.

Specification of Letters Patent.

Patented July 28, 1914.

Application filed June 25, 1913. Serial No. 775,644.

To all whom it may concern:

Be it known that I, JAMES F. MACWILLIAM, a citizen of the United States, residing at Worcester, in the county of Worcester and State of Massachusetts, have invented a new and useful Cop-Winder, of which the following is a specification.

This invention relates to a cop winder of the type in which the yarn is fed through a traversing guide to a conical cop former and in which the cop is wound upon a spindle rotating within the former. In machines of this type heretofore used it has been the common practice to mount the cop former rigidly upon the frame of the machine. This construction has been productive of more or less inconvenience and difficulty in removing the cops from the machine, and specially constructed spindles have been required in order to permit the doffing to be accomplished.

It is one of the objects of my invention to provide a machine in which the cop former is movably mounted so that it may readily be removed from operative position when it is desired to doff the spindle.

Another object of my invention is to provide a machine in which each spindle may be disconnected from the common driving means independently of the remaining spindles.

A still further object of my invention is to provide a machine having a movable cop former in which movement of the former from operative position will disconnect the spindle from the driving mechanism.

With these objects in view my invention contemplates the construction of a machine in which the cop former is pivotally mounted for vertical movement and is held in operative position by a manually movable supporting member. Each spindle is provided with a separate driving pulley and with clutch mechanism by which the pulley can be disconnected from the spindle at will. Connections are also provided between the movable cop former and one member of the clutch mechanism whereby the removal of the former from operative position will disconnect the driving mechanism.

My invention further consists in certain devices, combinations and arrangements of parts which will be hereinafter described and more fully set forth in the appended claims.

A preferred form of my invention is

shown in the accompanying drawings, in which—

Figure 1 is a side elevation of one spindle of a cop winder together with such other parts of the winder as are necessary for a clear understanding of my invention; Fig. 2 is a longitudinal sectional view taken through the axis of the spindle bearings; Fig. 3 is a detail sectional view taken on the line 3—3 of Fig. 1; Fig. 4 is a similar view taken on the line 4—4 of Fig. 1; and Fig. 5 is a detail section taken on the line 5—5 in Fig. 1 and showing the construction of the weight attaching plate.

In the machine embodying my invention the cop is formed upon a horizontal rotating spindle 10, the yarn 11 being conducted to the spindle in the usual manner through the guide 12 over a frictional guide wheel 13 mounted upon a portion 14 of the frame of the machine, and thence through the traversing guide 15 to the cop former 16. The guide 15 is mounted upon an arm 17 secured to a shaft 18 extending longitudinally of the machine. It will be understood that in machines of this type a plurality of spindles 10 are provided, mounted in parallel relation throughout the length of the machine, and that a guide 15 and arm 17 is provided for each spindle. The shaft 18 to which the arms are secured extends the entire length of the machine and is provided with an arm 19 connected by a link 20 to a crank pin 21 mounted on a disk 22 and rotating with a shaft 23. The arm 19 may be provided with a slotted connection with the link 20 by which the traverse of the guide 15 may be adjusted.

The spindle 10 is mounted for both rotary and longitudinal movement in bearings 24, 25 and 26 as shown in Figs. 1 and 2. The bearing 25 is provided with an adjustable cap which may be clamped tightly upon a sleeve 27 secured therein. This sleeve extends to the left of the bearing 25 as shown in Fig. 2, and has loosely mounted thereon a pulley 28 which may be driven in any suitable manner, as by the belt 29. Rotatably mounted within the sleeve 27 is a second sleeve or bushing 30 provided with a square exterior portion 31, a reduced cylindrical portion 32, and a flange 33. The cylindrical portion 32 rotates freely in the bearing 26 while the flange 33 and the left hand end of the square portion 31 prevent longitudinal movement of the bushing rela-

tive to the bearing. The right hand end of the square portion 31 likewise serves as a shoulder to limit longitudinal movement of the pulley 28 on the sleeve 27. The bushing 30 is furthermore provided with a square hole extending axially therethrough, within which the square portion 34 of the spindle 10 is longitudinally movable. The spindle 10 is also provided with a reduced cylindrical portion 35 upon which is loosely mounted a sleeve 36 having an end flange or plate 37. This plate, as clearly shown in Fig. 5, is provided with a notch 38 and with a lateral projection to which is secured an eye 39. A weight 40 is secured to the eye 39 by a cord 41 passing over a guide wheel 41^a and tends at all times to move the spindle 10 yieldingly toward the right in Fig. 1. A rib 41^b is secured to the frame of the machine and co-operates with the notch 38 to prevent rotation of the sleeve 36 with the spindle 10, the plate 37 sliding longitudinally along said rib as the spindle is moved to the left in the operation of the machine.

25 Mounted upon the square portion 31 of the bushing 30 is a clutch member 42 provided with a square hole and freely movable along the square surface of the bushing. The clutch member is provided with jaws 43 co-operating with jaws 44 on the driving pulley 28 to transmit power from the pulley to the spindle 10.

The cop former 16 previously referred to is shown in Figs. 1 and 4 as having a partial conical shape and as being open upon its upper side. The cop former is secured to an arm 45 pivotally mounted on the frame of the machine at 46 and having a depending arm 47 to which is secured one end of a link 48. The other end of the link 48 passes loosely through a hole 49 in an arm 50 (see Fig. 3) mounted upon a vertical shaft 51. This shaft has a bearing 52 in the frame of the machine and has secured to its upper end a yoke 53 provided with pins 54 extending into a circular groove 55 in the clutch member 42. The rod 48 is yieldingly connected to the arm 50 by a spring 56 as shown in Fig. 1. The arm 50 is held against a collar 57 by the pressure of the spring 56 and a second collar 58 is mounted upon the link 48 to receive the outward thrust of the spring 56.

The cop former 16 mounted upon the arm 45 is held in raised position by a supporting member or brace 59 pivotally mounted upon a stud 60 secured to a bracket 61 mounted upon the frame of the machine. The supporting member 59 is provided with a laterally offset weighted handle or operating arm 62, and the bracket 61 has a vertical extension 61^a which overlies the arm 45 and limits upward movement thereof.

In the operation of my device the yarn is 65 secured to the spindle when the latter is in

extreme right hand position, as shown in Fig. 1, and the cop former is raised to the position also shown in that figure, when the weighted handle 62 will automatically swing the supporting member 59 under the arm 45, and maintain the cop former in operative position. As the cop former is raised the arm 47 will move the link 48 to the right in Fig. 1, thus engaging the clutch member 42 with the driving pulley 28 and starting the rotation of the spindle 10. Should the teeth 43 be in direct alinement with the teeth 44 when the link 48 is moved to the right, the spring 56 will yield sufficiently to prevent injury to the operating parts and the clutch member 42 will be pressed yieldingly toward the pulley 28 until the co-operating teeth have moved into proper relation with each other.

In my device, as in other machines of this type, the yarn is moved backward and forward by the guide within the length of the cop former 16 and as the cop is built up, the conical end thereof bears against the former and gradually pushes the spindle 10 toward the left, thereby raising the weight 40. When a sufficient amount of yarn has been wound upon the spindle the operator raises the handle 62, thereby removing the supporting member 59 and allowing the cop former 16 to drop. This movement of the cop former is communicated through the link 48 to the clutch member 42, moving the latter to the left, and thus disconnecting the driving mechanism. Furthermore, when the cop former 16 is removed from operative position the weight 40 is free to act upon the spindle 10 and will return the same to initial position, the newly formed cop moving to the right of the cop former and being in convenient position for doffing.

If desired the spindle may be started in rotation after doffing, before the yarn is attached thereto, the open upper side of the cop former affording access to the spindle so that the yarn may be attached while the spindle is in motion. This results in a material saving of time on some classes of work, the yarn being more readily secured to the spindle when in rotation.

It is evident that many changes and modifications can be made in the construction of my invention by those skilled in the art without departing from the spirit thereof, and I do not wish to be limited to the precise construction herein disclosed, but

What I do claim is:—

1. A cop winder having in combination a vertically movable open-sided cop former, a spindle rotatable therein, driving means for said spindle, and connections from said former to said driving means whereby downward movement of the former from operative position will disconnect the spindle from the driving means.

2. A cop winder having in combination an open-sided movable cop former, a longitudinally movable spindle rotatable therein, driving means for said spindle, connections 5 from said former to said driving means, whereby movement of the former will disconnect the driving means from the spindle, and means to automatically return said spindle to initial longitudinal position.
- 10 3. In a cop winder, a movable cop former, a rotatable spindle, driving means therefor comprising a pulley carrying one member of a jaw clutch and a second clutch member longitudinally movable relative to said pulley, and yielding connections from said former to said second member for yieldingly engaging said clutch members when the former is moved to operative position.
- 15 4. In a cop winder, a spindle, driving mechanism therefor, a movable cop former, means to maintain said former in operative

position, and connections through which removal of the former from operative position will disconnect said spindle from said driving means.

5. A cop winder having in combination a spindle, driving means therefor including a clutch member longitudinally movable relative to said spindle, a yoke for moving said clutch member longitudinally, a pivot arm 30 supporting a cop former, and a yielding link connecting said pivoted arm to said yoke, whereby the cop former and the clutch member may be moved simultaneously from operative position.

In testimony whereof I have hereunto set my hand, in the presence of two subscribing witnesses.

JAMES F. MACWILLIAM.
